PERPETUAL CALENDAR

James Moir Crabb, Sr., Lockport, Ill.

Application March 7, 1940, Serial No. 322,827

10 Claims. (Cl. 40—109)

My invention relates to improvements in perpetual calendars, and an important object of the invention is to provide a simple, convenient, and efficient arrangement of this character which is readily adaptable to different decorative schemes and which provides an unusually useful and attractive assembly.

Other important objects and advantages of my invention will be apparent from a reading of the following description taken in connection with the appended drawings, wherein for purposes of illustration I have shown preferred embodiments of my invention.

In the drawings:

Figure 1 is a general front or face view of an embodiment of the invention.

Figure 2 is a vertically foreshortened side or edge elevational view of Figure 1 looking from right to left.

Figure 3 is a general vertical transverse sectional view taken through Figure 1 approximately on the line 3—3 and looking toward the left in the direction of the arrows.

Figure 4 is a face view of one of the month cards.

Figure 5 is a horizontal sectional view taken through Figure 1 approximately on the line 5—5 and looking downwardly in the direction of the arrow.

Figure 6 is a horizontal sectional view taken through Figure 1 approximately on the line 6—6 and looking downwardly in the direction of the arrow.

Figure 7 is a fragmentary horizontal sectional view taken through Figure 1 approximately on the line 7—7.

Figure 8 is a fragmentary face view of one of the leap-year month cards.

Figure 9 is a face view of a portion of the year band.

Figure 10 is a fragmentary view similar to Figure 3 of another embodiment of the invention which eliminates the separate month card receptacle and in which all of the month cards are registered while one of them is in use.

Referring in detail to the drawings the numeral 5 generally designates the present calendar which consists of a backboard 6 of generally rectangular vertically elongated form, made of suitable stiff material such as cardboard, fiber, lightweight metal, or composition material in accordance with the selection of the maker, face or front side of the backboard 6 having extending completely thereacross the lower cross member 7 from the opposite ends of which rise side members 8 and 9, 55

respectively. The members 7, 8 and 9 have spacers 10, as shown in Figure 7, securing them to the front of the backboard 6 so that laterally inward portions of the elements 7, 8 and 9 are spaced from the backboard so as to provide grooves for reception of the interchangeable picture cards 11, of which six are provided, with different views on opposite sides of each of the picture cards, together with a designation such as that indicated by the numeral 12, applying to the month during which the particular picture is to be exhibited, so that a pertinent picture is provided for each month of the year.

Slidably mounted by and between the horizontal element 7 and the lower horizontal element 18 is the slide frame comprising two uprights 13 and 13', respectively, which are spaced from the side edges of the plate 6 and from each other a sufficient distance to slidably receive therebetween the month cards 14, the elements 13 and 13' being spacedly secured by spacers 15 to the front face of a rectangular plate 16 which is slidable on the face of the plate 6 as indicated in Figure 5, the arrangement providing grooves for reception of the edge of the month card 14 as indicated in Figure 5, the month card then occupying a position in front of the face of the plate 16. A stop strip 17 is secured between the lower ends of the uprights 13 and 13' to be engaged by the bottom edge 19 of the plate 6 when the month card is in place. The lower horizontal strip 18 is fastened across the lower end portion of the plate 6 as illustrated in Figure 1. Attached to the lower edge 19 of the plate 6 is a narrow month card receptacle 20 which is composed of a back plate 6', being an extension of the plate 6, a front plate 21 coextensive therewith, two uprights 22 and 23 and a front plate 24 which is spaced by the uprights 22 and 23 from the plate 21 as illustrated in Figure 6, thereby providing a receptacle for the month cards 14, including the leap-year cards 14'. The receptacle 20 contains all of the month cards including the leap-year cards except the one which is in use in the display frame above the receptacle.

As indicated in Figure 3 at the point designated by the respective numerals 25 and 26, the upper and lower edges of the display frame composed by the elements 13, 13' and 17, have projecting flanges which engage in grooves in the cross members 7 and 18, respectively, so as to be slidable between these members for a purpose to be described.

The face of the back plate 6 between the cross members 7 and 18 is provided adjacent the

member 7 with a line 28 which is composed of spaced abbreviations for the different days of the week beginning with Wednesday at the left hand extremity and extending through three weeks and ending at the right hand extremity with Tuesday. A slot 29 is formed in the plate 16 of the display frame to overlie the line 28 and is long enough to embrace an entire week, this slot 29 being located centrally in the upper part of the plate 16. Below the slot 29 the plate 16 has horizontally aligned and spaced slots 30 and 31 which are long enough to embrace an entire week on the longer line of week-day designations 32 located in a position spaced below the line of week days which is designated by the numeral 28, on the face of the plate 6. It is obvious that the frame is slideable relative to the lines 28 and 32 so as to cause the respective slots 29, 30 and 31 in the plate 16 to subtend the portions of the lines 28 and 32 selected by the operator.

The six ordinary month cards 14 and the two leap-year month cards 14' have slots 29', 30' and 31', corresponding in size and position with the slots 29, 30 and 31 so that these slots register when any month card is in the frame. Each month card has above its slot 29' a designation 33 of the particular month involved, as indicated in Figure 4. In the case of one of the cards, the designation 33 above the slot 29' is December, and in the proper sequence the designation 33 above the slot 30' will be November, while the designation above the slot 31' will be January, these being the next preceding and next succeeding months. Below the respective slots are horizontal and vertical rows of numerals in an assembly 34 similar to the ordinary arrangement of a month calendar, the vertical columns being spaced and arranged to correspond with and register with the day of the week designations on the rows 28 and 32 on the face of the back plate 6, each assembly having the proper number of days in accordance with the number of days in that particular month, and the numeral 1 being located in the vertical column which is applicable. On the rear of each month card is an arrangement of three month calendars similar to those described and similarly related to the various slots, with the designation 33 above the upper slot being one month in advance of the month on the face of the card, in the case of the card illustrated in Figure 4, the designation 33 on the reverse side is November, the left hand calendar October, and the right hand calendar December. In the case of each of the twelve months of the year, there is a similar relation to the two adjacent months on the front and back of the month card. Each month card and its designation 35 at its top is to be related in position with the successive year designations on the strip 36 which are exposed in a horizontal slot 37 in the cross member 1 and back plate 6, as illustrated in Figure 1.

The leap-year month cards 14' are similar in general arrangement to the ordinary month cards 14 except that the upper designations 33 and the month tabulations 35 are of a color contrasting with those of the similar portions of the ordinary month cards, and the numerals in the various calendars are suitably rearranged to correspond with the condition obtaining in leap-years. It will be obvious that when figuring dates relative to a leap-year, the corresponding leap-year month cards will be used in the sliding frame instead of the ordinary month card.

From the foregoing it will be evident that hav-

ing placed the month tabulation 35 under the proper year on the strip 36, a one move operation will show the days of the weeks, the number of days in the month, the number of days in the month that has passed and the number of days in the month to follow; also for the present year, the year that has passed, and the year that is to follow. Thus to find a certain day in a certain month in the present year, the past year, or the next year, it is only necessary to move the sliding frame along until the month wanted has its tabulation 35 aligned under the year selected on the strip 36, and the information is shown in the various slots described. It will be obvious that only two leap-year cards are necessary, each having an appropriate set of month calendars on the opposite sides thereof.

When the month related to the month currently in the frame has expired, the card is taken out of the frame and turned around or reversed and put back in the frame to expose the next succeeding month thereon. The frame is then moved to place the tabulation 35 under the correct year on the strip 36. When this second month has expired the card is removed from the frame, reversed, and placed at the back of the idle month cards in the receptacle so that the cards will be in proper rotation in the receptacle.

When years other than those exposed in the slot 37 are to be employed, the endless band 40, running on upper and lower rollers 41 and 42 supported by vertical side members 43 and 44 on the back of the backboard 6, is moved so as to expose other strips 36 in the slot 37 having the required year designating numerals 45 thereon. The numerals 45 are, of course, appropriately spaced relative to each other or placed side by side on the strips 36 in accordance with calendar requirements.

Referring to the embodiment shown in Figure 10 of the drawings, this is similar in all respects to the embodiment described except that the month card receptacle below the cross member 18 is omitted and the construction of the slide frame 14a amplified sufficiently to accept all of the ordinary month and leap-year month cards 14 with the various slots 29', 30' and 31' of these cards registering with their respective slots two of which are shown at 29a and 30a in the slide plate 16. The reference characters 6 and 42a designate the back plate 6 and one of the rollers respectively. The operation of this embodiment is as described above.

It is obvious that either of the described embodiments may be in the form of a one year calendar capable of reference only to the next preceding and next succeeding years by making the strip 36 stationary.

Although I have shown and described herein preferred embodiments of my invention, it is to be definitely understood that I do not desire to limit the application of my invention thereto, and any change or changes may be made in the construction and arrangement of the parts, which fall within the scope of the subjoined claims.

Having described the invention, what is claimed as new is:

1. A calendar of the type described, said calendar comprising a backboard, a pair of vertically spaced horizontal slides extending on the face of said backboard, a horizontally slideable frame mounted between said slides, said frame comprising a plate having upper and lower openings, an upper week-day line on the face of said backboard for showing through the upper opening, a

lower week-day line on the face of said backboard for showing through the lower openings in said plate, a month card, vertical slides on said frame for slidable reception of the month card, said month card having upper and lower openings to register with the openings in the plate of said frame.

2. A calendar of the type described, said calendar comprising a backboard, a pair of vertically spaced horizontal slides extending on the face of said backboard, a horizontally slidable frame mounted between said slides, said frame comprising a plate having upper and lower openings, an upper week-day line on the face of said backboard for showing through the upper opening, a lower week-day line on the face of said backboard for showing through the lower openings in said plate, a month card, vertical slides on said frame for slidable reception of the month card, said month card having upper and lower openings to register with the openings in the plate of said frame, a linear series of consecutive year designations exposed through an opening in the upper horizontal slide, a month tabulation on the upper edge of the month card for registration with the appropriate one of the year designations.

3. A calendar of the type described, said calendar comprising a backboard, a pair of vertically spaced horizontal slides extending on the face of said backboard, a horizontal slidable frame mounted between said slides, said frame comprising a plate having upper and lower horizontal slots, an upper week-day line on the face of said backboard for showing through the upper slot, a lower week-day line on the face of said backboard for showing through the lower slots in said plate, a month card, vertical slides on said frame for slidable reception of the month card, said month card having upper and lower slots to register with the slots in the plate of said frame, a linear series of consecutive year designations exposed through an opening in the upper horizontal slide, a month tabulation on the upper edge of the month card for registration with the appropriate one of the year designations, each slot of the month card being of a length to encompass seven week-day designations of the corresponding week-day line on the face of the backboard.

4. A calendar of the type described, said calendar comprising a backboard, a pair of vertically spaced horizontal slides extending on the face of said backboard, a horizontal slidable frame mounted between said slides, said frame comprising a plate having upper and lower horizontal slots, an upper week-day line on the face of said backboard for showing through the upper slot, a lower week-day line on the face of said backboard for showing through the lower slots in said plate, a month card, vertical slides on said frame for slidable reception of the month card, said month card having upper and lower slots to register with the slots in the plate of said frame, a linear series of consecutive year designations exposed through an opening in the upper horizontal slide, a month tabulation on the upper edge of the month card for registration with the appropriate one of the year designations, each slot of the month cards being of a length to encompass seven week-day designations of the corresponding week-day line on the face of the backboard, a calendar layout related to each of the slots on the month card.

5. A calendar of the type described, said cal-

endar comprising a backboard, a pair of vertically spaced horizontal slides extending on the face of said backboard, a horizontally slidable frame mounted between said slides, said frame comprising a plate having upper and lower horizontal slots, an upper week-day line on the face of said backboard for showing through the upper slot, a lower week-day line on the face of said backboard for showing through the lower slots in said plate, a month card, vertical slides on said frame for slidable reception of the month card, said month card having upper and lower slots to register with the slots in the plate of said frame, a month card receptacle under the lower horizontal slide, said receptacle containing six regular month cards and two leap-year month cards, each of the month cards having consecutive month calendars arranged on the opposite faces thereof.

6. A calendar comprising a support comprising a main plate, upper and lower rollers supported behind said main plate, a ribbon mounted on said rollers having transverse rows of year designations thereon for selective exposure through a horizontal opening formed in said main plate, a pair of vertically spaced slideways on the front of said main plate below said horizontal opening, a slide frame supported for horizontal adjustment in front of said main plate by said slideways, means comprising at least one month card carried by said slide frame, said month card having a tabulation at its upper edge arranged to be aligned with a selected one of the year designations of the selected one of said rows of year designations exposed through said horizontal opening.

7. A calendar comprising a support comprising a main plate, upper and lower rollers supported behind said main plate, a ribbon mounted on said rollers having transverse rows of year designations thereon for selective exposure through a horizontal opening formed in said main plate, a pair of vertically spaced slideways on the front of said main plate below said horizontal opening, a slide frame supported for horizontal adjustment in front of said main plate by said slideways, means comprising at least one month card carried by said slide frame, said month card having a tabulation at its upper edge arranged to be aligned with a selected one of the year designations of the selected one of said rows of year designations exposed through said horizontal opening, an upper horizontal line of consecutive week-day designations on said main plate adjacent to but below the upper slideway, a single upper horizontal slot formed in said month card arranged to expose seven consecutive week-day designations in said upper line, a month calendar layout on said month card below said upper slot having its vertical columns of date numerals arranged for alignment with the selected seven week-day designations of said upper line.

8. A calendar comprising a support comprising a main plate, upper and lower rollers supported behind said main plate, a ribbon mounted on said rollers having transverse rows of year designations thereon for selective exposure through a horizontal opening formed in said main plate, a pair of vertically spaced slideways on the front of said main plate below said horizontal opening, a slide frame supported for horizontal adjustment in front of said main plate by said slideways, means comprising at least one month card carried by said slide frame, said month card having a tabulation at its upper edge arranged

to be aligned with a selected one of the year designations of the selected one of said rows of year designations exposed through said horizontal opening, an upper horizontal line of consecutive week-day designations on said main plate adjacent to but below the upper slideway, a single upper horizontal slot formed in said month card arranged to expose seven consecutive week-day designations in said upper line, a month calendar layout on said month card below said upper slot having its vertical columns of date numerals arranged for alignment with the selected seven week-day designations of said upper line, a lower horizontal line of consecutive week-day designations on said main plate below the upper line, a horizontally aligned pair of lower slots formed in said month card below said single upper slot, a preceding month calendar layout on said month card below one of the lower slots and a succeeding month calendar layout below the remaining lower slot, said lower slots each being arranged to expose seven consecutive week-day designations on the lower line, whereby for any selected year, the date and name of the day of the week is shown for the current month, the preceding month, and the succeeding month.

9. A calendar comprising a support comprising a main plate, upper and lower rollers supported behind said main plate, a ribbon mounted on said rollers having transverse rows of year designations thereon for selective exposure through a horizontal opening formed in said main plate, a pair of vertically spaced slideways on the front of said main plate below said horizontal opening, a slide frame supported for horizontal adjustment in front of said main plate by said slideways, means comprising at least one month card carried by said slide frame, said month card having a tabulation at its upper edge arranged to be aligned with a selected one of the year designations of the selected one of said rows of year designations exposed through said horizontal opening, an upper horizontal line of consecutive week-day designations on said main plate ad-

jacent to but below the upper slideway, a single upper horizontal slot formed in said month card arranged to expose seven consecutive week-day designations in said upper line, a month calendar layout on said month card below said upper slot having its vertical columns of date numerals arranged for alignment with the selected seven week-day designations of said upper line, said means consisting of six ordinary month cards and two leap-year cards arranged in succession from front to rear.

10. A calendar comprising a support comprising a main plate, upper and lower rollers supported behind said main plate, a ribbon mounted on said rollers having transverse rows of year designations thereon for selective exposure through a horizontal opening formed in said main plate, a pair of vertically spaced slideways on the front of said main plate below said horizontal opening, a slide frame supported for horizontal adjustment in front of said main plate by said slideways, means comprising at least one month card carried by said slide frame, said month card having a tabulation at its upper edge arranged to be aligned with a selected one of the year designations of the selected one of said rows of year designations exposed through said horizontal opening, an upper horizontal line of consecutive week-day designations on said main plate adjacent to but below the upper slideway, a single upper horizontal slot formed in said month card arranged to expose seven consecutive week-day designations in said upper line, a month calendar layout on said month card below said upper slot having its vertical columns of date numerals arranged for alignment with the selected seven week-day designations of said upper line, said means consisting of six ordinary month cards and two leap-year cards arranged in succession from front to rear.

JAMES MOIR CRABB, SR.
